UNITED STATES PATENT OFFICE.

GEORGE WALKER, OF NEWTON CENTER, MASSACHUSETTS.

DRIVING MECHANISM FOR SHIPS' INSTRUMENTS AND OTHER PRECISION INSTRUMENTS.

Application filed January 25, 1923. Serial No. 614,834.

To all whom it may concern:

Be it known that I, GEORGE WALKER, a citizen of the United States of America, and resident of Newton Center, in the county of 5 Middlesex and State of Massachusetts, have invented new and useful Improvements in Driving Mechanism for Ships' Instruments and Other Precision Instruments, of which the following is a specification.

10 This invention relates to driving mechanism for precision instruments of the type in which one shaft is to be connected to and disconnected from another shaft during alternate intervals of time. The driven shaft 15 may actuate a counter or indicator which may be reset during the interval of rest.

The invention is particularly adapted for use in ships' instruments of the type disclosed in my copending applications Ser. 20 No. 273,744 filed January 19, 1919; Ser. No. 319,392 filed August 23, 1919, and Ser. No. 614,838, filed on even date herewith, wherein indicators are recurrently and alternately advanced from an initial position variable 25 distances depending upon the speed of the shaft the indicators being reset to initial position between successive advances.

Objects of the invention are to prevent irregularities in the indication made by the 30 indicator due to a sudden throw of the latter at the moment of making or breaking the driving connection thereby to produce an even and steady operation of the indicator, and in general to improve devices of the 35 class described and to make them more accurate and uniform in operation.

For the purpose of illustration one concrete embodiment of the invention is shown in the accompanying drawings, in which:—

40 Fig. 1 is a front elevation of the indicating portion of the device; and

Fig. 2 is an elevational view of the mechanism behind the dials shown in Fig. 1 for actuating the indicators.

45 The embodiment of the invention shown for the purpose of illustration comprises a pair of indicators 3 and 3' arranged to be alternately advanced around dials 4 and 4' by shafts 5 and 5' arranged, through the 50 medium of driven gear wheels 6 and 6' fast on shafts 5 and 5' respectively and intermediate trains of gears 7 and 7', to have a driving connection with a driving wheel 8 on shaft 9. Shaft 9 is operated by connections (not shown) at the same speed as some

rotating part such as a propeller shaft or at a speed proportional thereto if one propeller is used, or at the average speed or a speed proportional thereto if a plurality of propellers are used.

60 Intermediate gears 7 and 7' are rotatably mounted upon arms 10 and 10' pivoted for swinging movement about the axis of the driven wheels 6 and 6' respectively, the innermost of each train of gears being in mesh with the driven wheels respectively. Arms 10 and 10' are urged toward driving gear 8 by springs 11 and 11' fast at one end to extensions 12 and 12' on arms 10 and 10' respectively, and at the other to stationary 65 brackets 13 and 13' fast upon the back plate or support of the device. Adjusting means in the form of screws 14 and 14' may be provided to limit the inward movement of arms 10 and 10' to a position in which the outermost of the trains of gears 7 and 7' properly mesh with driving wheel 8 to prevent jamming.

70 The mechanism for controlling the operation of indicating shafts 5 and 5' preferably 75 comprises bars 15 and 15' adapted to be reciprocated manually or by suitable mechanism (not shown) such as that disclosed in my aforesaid applications. The reciprocating of the bars 15 and 15' serves to step 80 around shafts 16 and 16' through ratchet wheels 17 and 17' on said shafts and pawls 18 and 18' on said bars. Fast on shafts 16 and 16' are pinions 19 and 19' having elongate teeth. These teeth cooperate with bars 85 or arms 20 and 21' fast to extensions 12 and 12' of arms 10 and 10' alternately to force arms 10 and 10' outwardly against the tension of springs 11 and 11' to break the driving connection between wheel 8 and driven 90 wheels 6 and 6'. Pinions 19 and 19' also control levers 22 and 22' which in turn control clutch mechanism (disclosed in Ser. No. 614,835, filed on even date herewith) for normally preventing reverse movement of 95 wheels 6 and 6' to resetting position. Wheels 6 and 6' are further provided with escape- 100 ment and stop mechanism 23 and 23' of the type disclosed in my copending application Ser. No. 614,836 filed on even date here- 105 with.

110 The operation of the device is as follows: By the actuation of bars 15 and 15' at properly timed intervals pinions 19 and 19' are stepped around and control the operation of

shafts 5 and 5' in substantially the following order: Indicators 3 and 3' are alternately operated from shaft 9 during succeeding minutes. As shown in Fig. 1, indicator 3 is moving forward or clockwise. Indicator 3' is stopped at the indication registered during the preceding minute. Just before the minute is up during which indicator 3 is recording, indicator 3' will be reset. At the end of the minute indicator 3 will be stopped and indicator 3' will be started to count the propeller revolutions for the next minute. The position of the parts shown in Fig. 2 corresponds with those shown in Fig. 1; that is, arm 20 has slipped off one of the teeth of the pinion 19 due to a one-tooth rotation of shaft 16 actuated by bar 15 so that arm 10 has swung inwardly to mesh outermost gear of train 7 with gear wheel 8, thus completing the driving connection from gear 8 to driven gear 6. Arm 10' was simultaneously moved outwardly by arm 21' riding upon one of the teeth of gear 19' so that the driving connection between wheel 8 and wheel 6' is broken. Upon the next reciprocation of bar 15' arm 10' will still be retained in the position shown but lever 22' will be actuated to permit shaft 5' to be reset, and on the next reciprocation of bar 15', which occurs simultaneously with the reciprocation of bar 15, arm 21' will fall between adjacent teeth of pinion 19' and a driving connection will be established between driving wheel 8 and shaft 5', and the reciprocation of bar 15 will disconnect the driving connection between wheel 8 and shaft 5'. The arrangement of intermediate gears here shown between the driving and driven shafts has numerous advantages. In the first place the outermost gears of gear trains 7 and 7' are brought radially into mesh with driving wheel 8 resulting in a quick and accurate meshing of the wheels with little or no jiggle of the driven gears. Furthermore the pivoting of arms 10 and 10' upon which the trains of gears are mounted, about the axis of the driven gears 6 and 6' respectively, results in two advantages: (1) When the arms are swung inwardly to mesh the gears the innermost of each train rolls upon driven gears 6 and 6' in a direction to reverse its movement so that the indicators 3 and 3' are held in stopped position; (2) at the same time, due to the inability of gears 6 and 6' to turn, trains of gears 7 and 7' are caused to rotate in the directions respectively in which they turn in advancing the indicator, hence the outermost gears of trains 7 and 7' are rotating with driving wheel 8 rather than against it when they come into mesh, so that indicators 3 and 3' will start off evenly and smoothly upon their recording movement. The arrangement herein disclosed provides exceptionally accurate and uniform operation of the indicators with a minimum of wear upon the parts.

In the forms shown three small gears have been employed to form trains 7 and 7' respectively, but it is obvious that other numbers of such gears may be used. However, the use of a number of small gears permits a much more compact arrangement of parts than would one large gear arranged to make a radial contact in the same way. Moreover, the small gears provide more latitude in locating the centers of the driving and the driven gears so that the dimensions of the parts and of the device as a whole can be made to conform to any desired limit.

I claim:

1. Driving mechanism for precision instruments comprising a pair of driven wheels adapted to be alternately rotated by a driving wheel during succeeding intervals of time, means for making and breaking the driving connection between the wheels comprising members having a driving connection with the driven wheels and movable substantially radially into and out of contact with the driving wheel.

2. Driving mechanism for precision instruments comprising a pair of driven wheels adapted to be alternately rotated by a driving wheel during succeeding intervals of time, means for making and breaking the driving connection between the wheels comprising members having a driving connection with the driven wheels and mounted for swinging movement about the axis of said driven wheels, said members being movable into and out of contact with the driving wheel.

3. Driving mechanism for precision instruments comprising a pair of driven gears adapted to be alternately rotated by a driving gear during succeeding intervals of time, means for making and breaking the driving connection between the driving gear and each of the driven gears comprising a member pivoted for swinging movement about the axis of one of the gears and carrying a gear arranged to be moved radially into and out of mesh with the other gear, and means for simultaneously swinging said members to disconnect the driving gear from one driven gear and to connect the driving gear with the other driven gear.

4. Driving mechanism for precision instruments comprising a pair of shafts operating indicators adapted to be alternately rotated by driving shafts, a gear wheel on each of said shafts, and means for making and breaking the connection between the gear wheels on the several shafts comprising an arm mounted for swinging movement on each of said indicator shafts, a train of gears in mesh with each other on each arm, the first of said gears meshing with the

- wheel on the shaft and the outer of said gears being arranged to mesh substantially radially with the wheel on the driving shaft, and means for simultaneously moving said arms to make one of said connections and to break the other connection.
5. Driving mechanism for precision instruments comprising a pair of shafts operating indicators adapted to be alternately rotated by driving shafts, a gear wheel on each of said shafts, and means for making and breaking the connection between the gear wheels on the several shafts comprising an arm mounted for swinging movement on each of said indicator shafts, a train of 15 gears in mesh with each other on each arm, the first of said gears meshing with the wheel on the shaft and the outer of said gears being arranged to mesh substantially radially with the wheel on the driving shaft, 20 and means for moving each of said arms to make and break the driving connection.
- 10

Signed by me at Boston, Massachusetts, this 27th day of December, 1922.

GEORGE WALKER.
